UNITED STATES PATENT OFFICE.

WILLIAM ACKERMAN AND ALBERT A. HASSELQUIST, OF ELGIN, ILLINOIS.

WHEELED SCRAPER.

SPECIFICATION forming part of Letters Patent No. 568,595, dated September 29, 1896.

Application filed November 5, 1895. Serial No. 568,007. (No model.)

To all whom it may concern:

Be it known that we, WILLIAM ACKERMAN and ALBERT A. HASSELQUIST, of Elgin, in the county of Kane and State of Illinois, have invented a new and useful Improvement in Wheeled Scrapers, of which the following is a full, clear, and exact description.

Our invention relates to an improvement in wheeled scrapers, and especially to an improvement in the scraper for which Letters Patent were granted to us November 21, 1893, No. 509,278.

The object of the invention is to provide a scraper in which the scoop will be entirely under the control of one man, the manipulator being also capable of driving the team attached to the machine, and to so simplify and rearrange the parts of the machine that the entire machine will be under better control of said operator than heretofore, and whereby also the scoop may be much more readily and effectually carried to the dumping position or restored to the working position.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a side elevation of the machine, one of the supporting or traction wheels being removed. Fig. 2 is a plan view of the same. Fig. 3 is a rear elevation thereof. Fig. 4 is a partly sectional rear elevation taken substantially on a vertical plane coincident with the axle of the machine. Fig. 5 is a detail view of the right-hand disk, adapted as one of the supports for the scoop and likewise adapted as a locking-disk. Fig. 6 is a plan view of the draft-pole sheath and a portion of the pole of the machine. Fig. 7 is a longitudinal vertical section taken substantially on the line 7-7 of Fig. 6. Fig. 8 is a transverse sectional view through the axle, illustrating the connection with said axle of the rear portion of the scoop whereby the same may be readily elevated. Fig. 9 is a detail view of one of the bearings of the shift-

ing shaft; and Fig. 10 is a side elevation of the pole of the machine, illustrating the connection therewith of the draft device.

In carrying out the invention the ground or traction wheels 10 are loosely mounted upon an axle 11, and the inner face of the hub of each ground-wheel is provided with an attached ring or band 12, having clutch-teeth upon its inner face. Adjacent to the clutch-face of each traction-wheel a disk A is splined on the aforesaid axle, and each locking-disk comprises a cupped body 14, the body portions being carried over the clutch-rings 12 of the wheels, so as to exclude dust therefrom, and also a flange 15, which is located at the peripheral portions of the inner face of the body. This flange is preferably made wider at one side than the other, as illustrated particularly in Fig. 5, and the left-hand disk is adapted particularly as a locking-disk, having a pocket 17 made in the lower portions of the wider section of its flange, a shoulder 16 being formed at the upper portion of the said flange, as is likewise best shown in Fig. 5.

At each side of the longitudinal center of the axle a shifting sleeve 18 is mounted to slide upon the said axle and turn therewith. Each shifting sleeve is provided at its outer face with a flange 19, and bolts 20 are attached to the flanges of the said sleeves and are passed outwardly through openings made in the body portions of the disks A, and within the body portion of each disk a clutch-ring 21 is loosely mounted, and the said clutch-rings are secured to the bolts 20, as is particularly shown in Fig. 4, the clutch-rings of the shifting sleeves being adapted for engagement with the clutch-surfaces of the wheels, although they are normally held out of such engagement. Lugs 21^a are produced in the body of each disk A, being adapted for engagement with lugs 21^b, made upon the peripheries of the clutch-rings 21, in order to relieve the pressure upon the bolts 20, as shown in Fig. 4.

The frame of the machine may be said to comprise the yoke-section B. This yoke-section is loosely mounted upon the axle, as shown in Fig. 4, the mounting occurring adjacent to the inner faces of the shifting sleeves

18, and in addition to the yoke B the frame comprises a horizontal and longitudinal extension B' of the yoke, located over the central portion of the machine, being carried in 5 a forwardly direction.

The extension B' is hollow and its inner surface is so constructed as to form a slide-way 24, as is best shown in Figs. 6 and 7, for the reception of a slide 23. In the upper surface of the extension B' of the frame a horizontal slot 24^a is made, extending from the front to the rear, and the forward portion of the extension of the frame is in a measure closed by a strap or yoke-bar 25, and adjacent 10 to this bar a latch 26 is hinged upon one side of the frame extension, the said latch normally extending over the top of the extension and engaging at its opposite side with a keeper 27, as shown in Figs. 2, 6, and 7, and 15 to this bar a latch 26 is hinged upon one side of the frame extension, the said latch normally extending over the top of the extension and engaging at its opposite side with a keeper 27, as shown in Figs. 2, 6, and 7, and 20 normally the slide 23, contained within the frame, is prevented from moving at predetermined periods by reason of a stop 28, formed upon the upper forward portion of the slide, engaging with the latch 26. The latch 26 at 25 its pivot end is provided with an extension 26^a, shaped in such manner as to receive the foot of the operator, and the keeper 27 is of angular construction, as shown in Fig. 7, comprising a vertical and a horizontal member, 30 the horizontal member serving to limit the upward movement of the latch, and the said upward movement will be such as to permit of the passage of the stop 28 of the slide beneath the latch and likewise the passage of 35 a keeper 28^a, which is secured to and extends forwardly from a post or upright 29, located upon the rear portion of the slide, as is shown in Figs. 6 and 7.

It will be understood that the slide 23 consists of two parallel bars, as shown in Fig. 6. The forward or yoke-bar 25 of the extension-frame is higher than the latch when at its full upper position.

If in practice it is found desirable, friction-rollers may be placed at various points in the slide, so as to facilitate the travel of the latter in the extension of the frame, and this extension may be termed a "sheath" for the slide. The pole 30 is secured to the forward 45 end of the slide 23 in any suitable or approved manner.

The clutches adapted for engagement with the hub-sections of the supporting-wheels are operated through the medium of a shaft 31, 50 encircled and controlled by a spring 31^a, which shaft is journaled in bearings 32 and 33, secured to the under face of the extension of the frame, and one of the bearings 33 is illustrated in detail in Fig. 9, in which it will 55 be seen that the opening 34 through which the shaft is passed is slightly elongated. The rear bracket or bearing 33 is longer than the forward bracket. Therefore the shaft has a rearward and downward inclination, and the 60 aforesaid shaft is rocked either through the medium of a foot-lever 35 (shown best in Fig. 65

4) or a hand-lever 36, the hand-lever being at the left-hand side, and these two levers may be continuous, if in practice it is found desirable. Both of these levers, however, as 70 is likewise the latch at the front of the extension-frame, are within convenient reach from the driver's seat 37, the said seat being supported on a suitable standard 38, attached to the rear portion of the frame, usually the 75 rear bow-section B thereof.

The shifting shaft 31 carries at its rear end a disk 39, firmly secured thereto, and two arms 40 and 41 are pivotally connected with the said disk at diametrically opposite points 80 and the arms extend in opposite directions, one to an engagement with each of the shifting sleeves 18. The opening 34 in the lower hanger or bracket 33 of the shifting shaft permits the shifting arms to be so operated 85 that a single clutch may be brought into action at a time and be slid into connection with a traction-wheel 10.

A scoop C is supported at its sides by attaching to these faces upwardly-extending 90 arms 42, and these arms are pivotally attached to the disks A at the lower portion of the enlargement of their flanges 15, preferably just below the pocket 17 on the right-hand disk and at a corresponding point on the left-hand 95 disk, so that when the axle is revolved the disks are turned also, and the scoop will be carried upward or downward according to the direction in which the axle is turned. The scoop is locked in an upper or in a lower position by means of a locking-bolt 43, adapted for engagement with the shoulder 16 of the left-hand or locking disk when the scoop is in its lower or working position, as shown in Fig. 1, and this bolt will enter the pocket 17 100 of this disk when the scoop is raised, holding it in such position. This latch, as illustrated in Fig. 2, is preferably provided with a bifurcated rear section, and at its bifurcated point is pivoted to a rear upright 44^a of a substantially 105 U bracket 44, secured upon the left-hand portion of the rear frame-section B, the forward member 44^b of this bracket being adapted as a guide for the bolt, and the bolt is operated through the medium of a lever 110 45, which is preferably fulcrumed in the bifurcated portion thereof and is curved at its lower edge to bear upon the plane or bottom surface of the bracket 44.

The scoop is dumped after being raised to 115 an upper position by the action of the slide 23, the said slide being carried forward by the movement of the beam when the latch 26 is opened up. The attachment between the slide and the scoop is shown in Figs. 1, 2, and 120 8, as is likewise the attachment between the axle and the rear of the scoop, the latter attachment being for the purpose of so inclining the scoop as to insure all of the material being emptied therefrom.

The scoop is provided at the rear with an 125 upwardly and rearwardly extending ear 46,

and this ear is pivoted in an elongated slot 47, which is made in the rear end of the horizontal member of a substantially T-shaped arm D, and the forward end of the said member is upwardly curved and pivotally connected with a crank-arm 48, secured, preferably, upon the central portion of the axle 11, as shown in Fig. 8. The upper end of the vertical member of the said T-arm D is pivoted between the rear extremities of two links 49, these links being pivoted at their forward ends to the rear upright 29 on the slide 23. Stirrups 50 are preferably secured to the forward portion of the frame extension to receive the feet of the driver.

In order to facilitate the draft, an attachment is provided to the pole 30, (shown in Fig. 10,) whereby the draft will be obtained from the rear end portion of the pole, and to that end a link 51 is placed beneath the pole and is pivotally connected to a fixed clevis 52 at the heel of the pole; and the said link 51 is led beyond the forward extremity of the pole through a guide 53, being provided at the said forward end with means for attachment to a whiffletree.

The operation of the machine is substantially as follows: Taking it for granted that the scoop is in an upper position, in which event the locking-bolt 43 will be in the pocket 17 of the locking-disk A, when it is desired to drop the scoop to scrape the road this is accomplished by drawing the lever inward, thereby carrying the bolt 43 out of engagement with the said disk, and the scoop by reason of its weight will drop to the ground after the latch 26 has been raised to release the rear catch 28^a of the slide from engagement with it. After the scoop has dropped to the ground and as the horses are driven forward a predetermined distance, the bolt being then in engagement with the shoulder 16 through the medium of the lever 35 or 36, which may be operated by foot or by hand, the clutches on the axle will be brought into action and engage with the clutch-faces of the friction-wheels, therefore revolving said axle and causing the attached disks A to be carried upward, and they will carry with them the scoop. The scoop will continue to be raised until the locking-bolt 43 will have entered the pocket 17 of the left-hand locking-disk, whereupon the clutches are carried out of engagement with the friction-wheels, it being understood that the clutches can be operated either by the hand or the foot lever, the spring 31^a upon the shaft 31 releasing them when the pressure is relieved. The scoop being in its upper position, when the dumping-ground is reached, the driver will raise the latch 26, and the horses, drawing forward, will carry the slide with them, thereby tilting the scoop upon its pivotal support and causing the load to dump, the crank connection of the rear supporting-arm of the scoop with the axle being such that when the scoop is

tilted it will assume a position of steep inclination. When the slide has been carried forward to the full extent of dumping the scoop, the latch 28^a will have passed and become positively engaged with the latch 26, the said latch having been permitted to drop and hold the scoop in its dumping position. In order to carry the scoop downward again to the ground, the latch 26 is raised and the locking-bolt is disengaged from the left-hand disk by the operation of a hand-lever 45, and the weight of the scoop will carry it to its lower position. This return of the scoop may be aided, if necessary, by a backing of the horses. The object of the crank-and-lever connection between the axle and rear end of the scoop is to provide a pivotal mounting for the arm D, so that it may swing upwardly at its rear end in the manner above described. As the axle rocks, the crank-arm will swing and carry the arm D in a corresponding manner clear of the ground under all conditions.

Having thus described our invention, we claim as new and desire to secure by Letters Patent—

1. In a wheeled scraper, or similar machine, the combination, with an axle, traction-wheels loosely mounted thereon, and clutches mounted upon the said axle and adapted for engagement with the clutch-faces of the traction-wheels, of a frame loosely mounted upon the axle, a slide having movement in the said frame, a scoop pivotally supported from the axle at its sides, a crank connection between the axle and the rear of the scoop, said crank being connected with the said slide, and a locking device for the slide, as and for the purpose set forth.

2. In a wheeled scraper or similar machine, the combination, with an axle, traction-wheels loosely mounted on the axle and having their hubs provided with inner clutch-faces, clutches having sliding movement on the shaft, being adapted to turn therewith and being further adapted for engagement with the clutch-surfaces of the aforesaid wheels, shifting levers connected with the said clutches, disks mounted upon the said axle, a scoop having its sides pivotally connected with the said disks, and a locking device for one of the disks substantially as described, of a frame loosely mounted on the axle, a slide adapted for connection with the pole, having movement in the said frame, a crank-and-lever connection between the rear of the scoop and the central portion of the axle, a link connection between the aforesaid lever and the said slide, and locking devices for the slide, as and for the purpose set forth.

3. In a wheeled scraper or similar machine, the combination, with an axle, traction-wheels mounted upon the axle, clutches carried by the axle and adapted to turn therewith and likewise adapted for interlocking engagement with a surface of the traction-wheel, a shifting lever connected with the clutches, and a

- 5 scoop pivotally supported at its sides from projections on the axle, of a frame loosely mounted on the axle, a slide having movement in the frame, being adapted for engagement with the pole of the machine, a latch adapted as a lock for the said slide, which latch is provided with a foot extension, a keeper carried by the slide, adapted for engagement with the said latch, a stop likewise located on the slide, and a connection between the slide and the rear of the said scoop, the connection being such that when the slide is drawn forward the rear portion of the scoop will be elevated, as and for the purpose specified.
- 15 4. In a wheeled scraper or similar machine, the combination, with an axle, traction-wheels mounted on the axle, clutches carried by the axle and adapted to turn therewith, and likewise adapted for interlocking engagement with a surface of the traction-wheel, a shifting lever connected with the clutches, and a scoop pivotally supported at its sides from projections on the axle, of a frame loosely mounted on the axle, a slide having movement on the frame, being adapted for engagement with the pole of the machine, a latch adapted as a lock for the said slide, which latch is provided with a foot extension, a keeper carried by the slide, adapted for engagement with the said latch, a stop likewise located on the slide, a connection between the slide and the rear of the said scoop, the connection being such that when the slide is drawn forward the rear portion of the scoop will be elevated, 30 a crank-arm projected from the axle at its center, a T-lever pivotally connected with the said crank-arm, a sliding connection between the lever and the rear of the scoop, and a link connection between the upper portion of the lever and the aforesaid slide, substantially as shown and described.
- 35 5. In a wheeled scraper or similar machine, a frame, a scoop located beneath the frame, a slide adapted for connection with a pole operating in said frame and connected with the rear of the scoop, a latch capable of being operated by the foot, attached to the frame and crossing the slide, keepers located upon the said slide, adapted for engagement with the latch, and a limiting-keeper located on the frame and extending over the latch, as and for the purpose specified.
- 40 6. In a wheeled scraper or similar machine, the combination, with the axle, of traction-wheels the inner faces of the hubs whereof are provided with clutch-surfaces, clutches held to slide upon the said axle, means for operating the clutches, and disks attached to the axle, forming guides for the sliding clutches, which disks are adapted to support the scoop and extend over the hubs of the wheels, forming dust-guards therefor, substantially as described.
- 45 7. In a wheeled scraper or similar machine, supporting-disks for the scoop thereof, each disk being provided with a dished body con-

structed to extend over the hub of a traction-wheel and form a dust-guard, as and for the purpose set forth.

8. In a wheeled scraper or similar machine, 70 the combination, with the axle, the traction-wheels and clutches mounted to slide on the axle, of disks mounted on the axle, a scoop pivotally supported on the said disks, each of said disks consisting of a dished body 75 adapted to extend over the hub of a traction-wheel, and a marginal flange to which the scoop is connected, both disks serving as guides for the shifting sleeves of the clutches and as shields for the clutches, as and for 80 the purpose set forth.

9. In a wheeled scraper, the combination, with the axle and traction-wheels and clutches mounted to slide on the axle, of disks mounted on the axle, a scoop pivotally supported on 85 the said disks, each of said disks consisting of a dished body adapted to extend over the hub of a traction-wheel and a marginal flange to which the scoop is connected, both disks serving as guides for the clutches, one disk 90 being provided with a shoulder and a pocket in the margin of its flange, and a lever-operated bolt adapted to enter said pocket or engage with the said shoulder of the disk, as and for the purpose set forth. 95

10. In a wheeled scraper, the combination, with the axle, traction-wheels loosely mounted thereon and having the inner faces of their hubs toothed, disks located upon the said axle, each disk consisting of a dished body 100 extending over the toothed hub portion of a traction-wheel, one of the disks being provided with depressions, and a lever-operated bolt adapted to enter the depressions of the said disks, of shifting sleeves mounted to 105 slide upon the axle, a shifting shaft, arms having crank connection with said shaft and with the said sleeves, clutch-rings mounted to slide in the dished portions of the said disks, a rod connection between opposing 110 shifting sleeves and clutch-rings, said rods passing loosely through the body portions of the said disks, and a scraper pivotally supported from the said disks, as and for the purpose specified. 115

11. In a wheeled scraper or similar machine, the combination, with a scoop, a wheel-supported axle, disks mounted upon the axle, and arms connecting the scoop with the said disks, of an arm projected rearwardly from 120 the rear end of the scoop, a crank-arm secured upon the axle between the disks, a lever pivotally connected with the crank-arm and having sliding engagement with the rear of the scoop, and a slide adapted to be operated by the team, connected with the said lever, as and for the purpose specified.

12. In a wheeled scraper or similar machine, the combination, with a scoop, a wheel-supported axle, disks mounted upon the axle, 130 and arms connecting the scoop with the said disks, of an arm projected rearwardly from

the rear end of the scoop, a crank-arm secured upon the axle between the disks, a lever pivotally connected with the crank-arm and having a sliding engagement with the rear of the scoop, a slide adapted to be operated by the team, connected with the said lever, and a lock for the said slide, adapted to

be operated by the driver of the machine, as and for the purpose specified.
